UNITED STATES PATENT OFFICE.

AI VARNEY, OF NEW MARKET, NEW HAMPSHIRE.

TAILOR'S PRESSING-MACHINE.

SPECIFICATION forming part of Letters Patent No. 322,217, dated July 14, 1885.

Application filed September 13, 1880. (No model.)

To all whom it may concern:

Be it known that I, AI VARNEY, a citizen of the United States, residing at New Market, in the county of Rockingham and State of New Hampshire, have invented certain new and useful Improvements in Tailors' Pressing-Machines; and I do hereby declare the following to be a full, clear, and exact description of the invention, such as will enable others skilled 10 in the art to which it appertains to make and use the same, reference being had to the accompanying drawings, and to the letters or figures of reference marked thereon, which form a part of this specification.

15 This invention relates to that class of ironing-machines in which the pressure of the sad-iron upon the material being pressed is regulated by means of a series of foot and hand levers; and the invention consists in the 20 special construction of devices for adjusting the goose-arms at their point of connection with the main rocking lever, as hereinafter more fully described and claimed.

In the annexed drawings, Figure 1 is a perspective view of my improved ironing apparatus. Fig. 2 is a transverse section of the same. Fig. 3 is a rear view of the operating levers. Fig. 4 is a top view of the supporting-stand with sad-iron and operating arms or 25 levers. Figs. 5 and 6 are detail views showing the method of attaching the goose-arms to the main rocking lever, and Figs. 7 and 8 are detail sectional views showing the manner 30 of securing the goose-handle to its operating-arm.

35 A represents the table, which is provided with suitable end supports, *a a*, united by the braces or bars *a' a'*. On the top of this table, at its front side, is arranged the ironing-board *B*, which is secured at its larger end to the slotted cross-bar *b*, so as to be adjustable to 40 various heights by means of the pivoted cross-supports *c c d*, the double supports *c c* being also pivoted together through the lug *c'* at the bottom, and through a slot in the bar *b* at their upper ends, while the support *d* is pivoted to the bar *b*, at the top, and works in a rack, *b'*, at the bottom. The board *B* is adjustably supported at its small- 45 er end by the cross-bar *e*, between the standards *f f*, the bar *e* being adjustable to the required height by the screws *g g g*, passing

through it and the top bar, *h*, one of said screws also serving to steady the board. The top of the table is recessed at its rear side to receive the double supports *C C*, which are secured thereto by screws. These supports are formed into lugs at the top, which furnish a bearing for the pivot *i* of the main connecting-lever *D*, and are also formed into similar lugs at the bottom that provide a bearing for 55 the bell-crank lever *E*, beneath the table. These levers *D E* are connected by the yokes *l l*, so as to cause them to move together, and the lever *E* is pivoted at its forward end to the rod *F*, which is in turn journaled to the treadle *G*, the latter being pivoted to the lugs *m m* on the rear bar *a'*, and working between the guides *n n* on the front bar *a'*. To this treadle is attached a rope or cord which passes 60 over a pulley secured to the under side of the table, and carries at its end a suitable weight. 65

On the upper end of the main lever *D*, at its front side, are formed two lugs or bearings, *k k*, for the vertical shaft *H*, which also 70 passes through bearings in the end of the main goose arm or lever *I*. The shaft *H* is hollow at its upper end, and is provided internally with screw-threads for the reception of the thumb-screw *K*, which has upon its shaft a 75 collar, *k'*. This screw is kept in place by the yoke *l'*, against which the collar *k'* abuts. A washer or ring, *p*, surrounds the shaft *H*, between the lugs or bearings on the ends of the arm *I*, and is secured to the shaft by a pin, so 80 that as the shaft is raised or lowered by turning the thumb-screw *K* it carries with it the arms or 85 levers *I J* and the sad-iron *L* attached thereto. The curved lever or arm *J* is pivoted to the arm *I* and provided with a stop, *r*, that prevents its backward rotation on said arm. On 90 the outer end of the arm *J* is a lug or enlargement through an orifice in which passes the loosely-fitting pin *s*, the rounded end of which is perforated or slotted for the reception of 95 the pin *t*, forming part of the goose-handle. This pin *t* passes loosely through the sleeve *n* and head of the pin *s*, and unites the goose or sad-iron *L* and its handle to the lever *J* in such a manner that the iron may be readily 100 turned in any required direction. The hollow sad-iron is provided with a small door at one end, and is thus adapted to be heated by slugs in the usual manner.

The operation of the apparatus is as follows: The board B having been adjusted to the required height by means of the screws *g g g* at one end and the cross-supports *c c d* 5 at the other, and the material to be pressed being placed thereon, the heated sad-iron is adjusted to the desired height by turning the thumb-screw K, which, engaging with the internally-threaded hollow shaft H, raises or 10 depresses the arms I J, to which the said iron is attached. While the cloth or other material is being pressed, it will be observed that, owing to the flexible connection of the sad-iron with the lever J and the adjustability of 15 the various parts of the apparatus, the iron may be readily moved in any desired direction with perfect facility, and the degree of its pressure upon the material varied instantaneously from time to time, as required, by 20 pressure of the operator's foot upon the treadle G, which pressure is immediately relaxed upon removal of the foot by means of the weighted cord attached to the treadle.

I am aware that in ironing-machines as heretofore constructed means have been provided 25 for vertically adjusting the goose-carrying arms independent of the rocking lever to which they are attached, and therefore I do not claim such adjustment broadly.

30 In Storr's Patent, No. 20,519, dated June 8, 1858, the jointed goose-arms are adjustably attached to the rocking lever by means of an externally-threaded pivot that passes through lugs on said lever and through a screw-threaded

35 aperture in the end of one of the jointed arms. In patent to Galley, No. 24,929, August 2, 1859, the arm is adjusted vertically by turning an externally-threaded sleeve that passes through a screw-threaded aperture in the end 40 of the arm, the sleeve being arranged to rotate on a vertical shaft having shoulders to pre-

vent displacement of the sleeve. In my machine it will be observed that the pivotal connection between the goose-arm and the rocking lever D is made by an internally-threaded 45 sleeve or hollow shaft, H, having a smooth external surface on which the goose-arm can turn without friction and without moving up and down while the sad-iron is in use. This hollow internally-threaded shaft H receives a 50 thumb-screw, K, by which said shaft is adjusted vertically, as required, thereby raising or lowering the goose-arms I J through the washer *p*, by which the parts are pivotally connected.

55 I am also aware of the patent to Howe, No. 119,708, dated October 10, 1871, which, however, does not embrace any means of vertically adjusting the goose-arm independent of the movement of the rocking lever to which it is connected.

Having thus described my invention, what I claim as new, and desire to secure by Letters Patent, is—

In a tailor's pressing-machine, the combination, with the rocking lever D, having lugs *k k* at its upper end, and the goose-arm I, having attaching-lugs, of the vertically-adjustable pivot-shaft H, having a smooth external surface and provided at its upper end with internal screw-threads, the washer *p*, secured to the external surface of said shaft between the lugs on arm I, and the thumb-screw K, having collar *k'* and yoke *l'*, as and for the purpose described.

70 In testimony whereof I affix my signature in presence of two witnesses.

75 AI VARNEY.
